UNITED STATES PATENT OFFICE.

HOMER A. GENEST, OF HARTFORD, CONNECTICUT, ASSIGNOR TO UNITED STATES HAT MACHINERY CORPORATION, OF NEW YORK, N. Y., A CORPORATION OF VIRGINIA.

METHOD OF AND APPARATUS FOR TREATING FELT ARTICLES.

Application filed March 26, 1924. Serial No. 701,997.

This invention relates to the shrinking of felt articles, for example bats from which fur or felt hats are made.

The aim of the invention is to provide an improved method and apparatus by means of which hat bats and the like may be shrunk and felted in such manner that superior articles are produced more economically than heretofore. More specific objects of 10 the present invention will be pointed out in detail in the following description.

The invention accordingly consists in the features of construction, combination of elements and arrangement of parts which will 15 be exemplified in the construction herein-after set forth, and the scope of the application of which will be indicated in the appended claims.

In the accompanying drawings, where- 20 in I have shown, for illustrative purposes, one embodiment which the machine of the present invention may take, and which machine is particularly adapted for use in carrying out my improved method of shrinking:

Figure 1 is a view showing, in top plan, my improved machine;

Fig. 2 is a side elevation with portions broken away;

Fig. 3 is a vertical longitudinal section taken on line 3-3 of Fig. 1; and

Fig. 4 is a view showing, in section, a bat passing between a pair of opposed rollers.

My improved apparatus, together with the 35 method involved in its use, may be employed in any stage of the shrinking or felting operation. It is, however, particularly adapted for use in the second or final sizing operation because it treats the bats with that 40 degree of severity which, owing to the fact that the fur or felt of the bats has already been felted to a considerable extent, is necessary. The machine may, of course, be constructed so as to give the bats a more or 45 less severe treatment as desired. It is clear that the present disclosure is by way of illustration only, it being evident that the machine is susceptible of various modifications and changes which would be within the 50 spirit of the invention without departing from the scope of the following claims. It is also understood that, while I have here

shown a specific machine for carrying out my improved method, the method is not limited to this particular machine.

In the illustrative showing of the drawings, the machine is provided with a plurality of rollers between which the bats are passed in an unrolled and saturated condition, and the construction and arrangement of 55 these rollers are such as to thoroughly manipulate and work all portions of the bats as they pass therethrough in such manner as to rapidly work the fibres into close interlocking relation without breaking or injuring 60 the fibres. In the present instance, the machine is shown as being provided with two series of rollers, each series comprising two sets or rows of rollers positioned one above the other. The bats are adapted to pass between the rollers of the first series in one 65 direction and then between the rollers of the other series in the opposite direction to the forward end of the machine. It is, of course, understood that but one, or more 70 than two, series of rollers can be employed, as preferred. As the rollers of the two series are similar in construction and arrangement, a description of the upper series 75 and the application of the reference numerals to that series will be sufficient for a clear understanding of the construction and operation of the machine.

The lower row of the rollers of each series, and which rollers serve to support the bats 80 as they are passed through the machine, are designated by the letter A, and the rollers which bear upon the bats are designated by the letter B. The rollers of the two rows are, in the present instance, opposed to each 85 other as will be seen most clearly from Fig. 3. Each roller has on its surface means for shifting, in a direction at right angles to that in which the bat is advanced through the machine, that portion of the ply of the 90 bat which the particular roller engages. These shifting means are so arranged that the opposed rollers tend to shift the two plies of the bat therebetween in opposite directions, and the adjacent rollers of each row 95 are constructed to shift the portions of the same ply of the bat which they engage in directions opposite to each other. More 100 specifically, each of the rollers, in the pres-

ent illustrative disclosure of the invention, is provided with a spiral rib or thread of relatively coarse pitch. The threads on the adjacent rollers of the same row run in opposite directions, for instance, the alternate rollers will have right hand threads or ribs and the intervening rollers will have left hand threads or ribs. The threads on the opposed rollers run in the same direction, that is to say, if the supporting roller had a right hand thread, then the roller B opposed to that supporting roller will have a right hand thread. The ribs or threads of the rollers are designated by the numeral 10 and the thread groove by the numeral 11. Each of the rollers is supported for rotation but is held against lengthwise or axial movement. Certain of the rollers are urged under pressure towards the opposed rollers in order to shift the plies relative to one another, and in the direction in which they are advanced, in a succession of small increments, as hereinafter described more in detail. In the present instance, those rollers which are urged under pressure against the opposed rollers are arranged in staggered relation, that is to say every other roller of the upper set or row is urged downwardly by springs, and the intervening rollers of the lower set or row are urged upwardly by springs or in any other desired manner. The remaining rollers are mounted in stationary bearings, and these other rollers are positively driven in a direction to advance the bats through the machine. The pressure rollers are not driven, except through their frictional engagement with the bats. For convenience, the pressure rollers of the upper set are designated by the letter B', and those of the lower set by the letter A'.

It will be seen from the construction so far described that, as the bat is fed through the machine, the thread or rib on the upper roller of the first pair will shift that portion of the upper ply of the bat passing thereunder in one direction, and the thread on the opposed lower roller will shift the lower ply of the bat in the opposite direction. The next upper roller will shift the upper ply in the direction opposite to that in which it is shifted by the first upper roller, and the second supporting roller will shift the lower ply in the direction opposite to that which this lower ply is being shifted by the first supporting roller and in the direction opposite to that which the second upper roller is shifting the upper ply. That is to say, the upper rollers alternately shift the upper ply in opposite directions and the lower rollers also shift the lower ply in opposite directions, and the opposed portions of the two plies are simultaneously shifted in opposite directions. Thus it will be seen that each ply is zig-zagged back and forth or is snaked, so to speak, in the plane of the

plies and in the direction in which the bats are advanced, and the snaking or zig-zagging of the upper ply is in the reverse order to that of the lower ply. Owing to the grooves in the rollers, the felt is bunched or ribbed, so to speak, into these grooves, thus forming waves 12 in the plies which are inclined, first in one direction and then in the other direction, and these waves extend generally in the direction in which the bats are passed between the rollers. Furthermore, owing to the fact that certain of the rollers are not positively driven and are adapted to move towards and away from the opposed rollers, there is formed in each of the plies a succession of transversely extending waves or ripples which are advanced through the plies in the direction in which the bat is moved through the machine, and thus each of the plies is progressively shifted in a succession of increments relative to the other ply. This results because each time the bat is brought into engagement with a pressure roller the movement of that portion of the bat which engages this roller is somewhat retarded so that immediately behind this roller a wave or ripple is made in the bat, and this wave is advanced as the bat moves forwardly. More specifically, the first pressure roller B' will form a transverse wave or ripple 13 in the upper ply; the second supporting roller, which is the first pressure roller of that row, forms a wave or ripple 14 in the lower ply; the third roller of the upper set, which is the second pressure roller of that set, will form a wave or ripple 15 in the upper ply, and so on, a wave being formed first in one ply and then in the other ply, and these waves being progressed in that order from the forward edge of the bat to the rear edge. Furthermore, it will be noted that, since the grooves in the rollers form ribs or waves 12 extending longitudinally of the bat, the transverse waves are more or less distorted, with the result that the bats immediately in advance of the pressure rollers will be given a peculiar action which greatly facilitates the felting and shrinking operation.

It will thus be seen that, as the bats pass through the machine, the two plies are pulled, pushed and manipulated in such manner that at one and the same time some portions of the bats are being shifted in one direction and other portions in the opposite direction, and the opposed portions of the two plies are shifted simultaneously in opposite directions. Not only are the plies shifted in their own planes transversely to the direction in which they are advanced, but waves or ripples are formed, both longitudinally and transversely of the bat, and the fibres of the plies are thus moved outwardly and then back into the plane of the plies, the final result of all these movements

being that the fibres are given such a sinuous, tortuous action that they are worked into each other very rapidly and thus the bats are properly felted and brought down to

5 the desired size. It will further be seen that, as the bat passes through the machine, it has applied to it in regular succession pressure, and this pressure is progressed throughout the bat from one edge to the other.

10 During the felting and shrinking operation, the bats are maintained in a moistened or saturated condition in any suitable manner but, in the drawings, there is shown, for this

15 purpose, a plurality of pipes 17 arranged above the rollers and adapted to discharge sprays of water onto the bats.

It is, of course, understood that the rollers which have been described may be supported in any suitable frame and driven in any de-

20 sired manner. In the drawings, I have shown the frame of the machine as comprising two side frames, each formed in sections (for instance, three sections 20, 21 and 22) in order to facilitate the mounting of

25 the bearing boxes 23 in which engage the ends of the pressure rollers A' and B'. The bearing boxes are mounted in suitable bores 24 and behind each bearing box is a spring 25, the compression of which may be regulated by screws 26. The stationarily mounted rollers of the lower series have on their left hand ends, as shown in Figs. 1 and 2, sprockets 28 driven by a chain 29 passing about a large sprocket 30 fixed to a driven

35 shaft 31. At the opposite or right hand end of the machine, the stationarily mounted rollers of the upper series are provided with sprockets 32 driven by a chain 33 in the same manner as does the chain 29 drive the sprockets 28. The chain 33 passes about a large sprocket 34 fixed on a shaft 35 which is driven through gears 36 from the shaft 31. 37 designates tapes at the forward end of the upper series of rollers for the purpose of feeding the bats into the machine.

40 38 are tapes which receive the bats as they are delivered from the lower series of rollers. 39 are guides for directing the bats from the upper series of rollers to the lower one. After a bat has passed through the machine, it may be taken from the delivery tapes 38 and again placed on the receiving tapes 37 so as to be again fed into the machine.

45 As many changes could be made in the above construction and many apparently widely different embodiments of this invention could be made without departing from the scope thereof, it is intended that 50 all matter contained in the above description or shown in the accompanying drawing shall be interpreted as illustrative and not in a limiting sense.

It is also to be understood that the language used in the following claims is in-

tended to cover all of the generic and specific features of the invention herein described and all statements of the scope of the invention which, as a matter of language, might be said to fall therebetween.

70 I claim as my invention:—

1. The herein described method of treating hat bats and the like, which consists in advancing the bat by a plurality of rollers having spiral ribs running in opposite direc-

75

2. The herein described method of treating hat bats and the like, which consists in simultaneously and progressively shifting spaced portions of each ply in opposite directions and simultaneously shifting abutting portions of the two plies in opposite direc-

80

3. The herein described method of treating hat bats and the like, which consists in progressively and successively applying pressure to the bat and simultaneously zigzagging each of the plies in the plane thereof and in the direction in which the pressure is progressed.

85

4. The herein described method of treating hat bats and the like, which consists in passing the bat flatwise in an unrolled condition between a plurality of members and causing said members to simultaneously shift spaced portions of each ply of the bat in opposite directions and abutting portions of the two plies in opposite directions.

90

5. The herein described method of treating hat bats and the like, which consists in passing the bat between a plurality of opposed rollers provided with threads on their peripheries, and rotating said rollers to cause spaced portions of each ply of the bat to be shifted simultaneously in opposite directions and abutting portions of the two plies in opposite directions.

95

6. The herein described method of treating hat bats and the like, which consists in forming in one ply of the bat zigzag waves and advancing said waves in the direction of their lengths.

100

7. The herein described method of treating hat bats and the like, which consists in progressively and successively applying pressure to the bat, forming in at least one ply of the bat zigzag waves spaced apart transversely of the direction in which the pressure is progressed, and advancing the waves through the said ply in the direction of their lengths.

105

8. The herein described method of treating hat bats and the like, which consists in progressively and successively applying pressure to the bat and advancing through each ply of the bat zigzag waves spaced apart transversely of the direction in which the pressure is advanced, the waves in one ply being reversed to those of the other ply.

110

9. The herein described method of treat-

115

- ing hat bats and the like, which consists in progressively and successively applying pressure to the bat, simultaneously moving spaced portions of one ply of the bat in opposite directions in a given plane, forming in said ply zigzag waves spaced apart transversely in the direction in which the pressure is advanced, and advancing said zigzag waves in the direction of their length.
- 10 10. The herein described method of treating hat bats and the like, which consists in snaking each of the plies in the planes thereof and advancing in each of the plies sinuous waves generally in the direction of the lengths of the waves.
- 11 11. The herein described method of treating hat bats and the like, which consists in progressively and successively applying pressure to the bat, simultaneously moving spaced portions and alternately moving the same portion of each ply of the bat in opposite directions, and advancing zigzag waves lengthwise in each of the plies, the waves of one ply being reverse to those of the other 25 ply.
- 12 12. The herein described method of treating hat bats and the like, which consists in snaking each ply of the bat generally in the planes thereof and at intervals humping portions of the plies out of their planes.
- 13 13. The herein described method of treating hat bats and the like, which consists in simultaneously and progressively moving spaced portions of a ply of a bat in opposite 30 directions and progressively shifting the ply relative to the other one in a direction transverse to that in which said ply is moved back and forth.
- 14 14. The herein described method of treating hat bats and the like, which consists in progressively and successively applying pressure to the bat, simultaneously moving spaced portions, and alternately moving the same portion, of one of the plies in opposite 35 directions and in the plane of the ply, forming zigzag waves in said ply and advancing the waves in the direction of their length, and shifting said plies relative to one another in successive increments in the direction of said zigzag waves.
- 15 15. The herein described method of treating hat bats and the like, which consists in zigzagging each ply of the bat in the planes thereof and progressively shifting each ply 40 of the bat relative to the other one in the general direction in which said plies are zigzagged.
- 16 16. The herein described method of treating hat bats and the like, which consists in simultaneously moving spaced portions and alternately moving the same portion of each 45 of the plies in opposite directions and advancing through each of the plies a succession of transversely extending ripples.
- 17 17. The herein described method of treat- 50 ing hat bats and the like, which consists in snaking each ply of the bat, advancing in each of the plies sinuous waves in the direction of the lengths, and progressively shifting the plies in the direction in which said waves are advanced.
- 18 18. The herein described method of treating hat bats and the like, which consists in progressively and successively applying pressure to the bat, simultaneously moving spaced portions and alternately moving the same portions of each of the plies in opposite directions in the plane of the plies, advancing through each of the plies waves extending generally in the direction in which the pressure is advanced, and in advancing transversely extending ripples in both of the plies in the direction in which the pressure is advanced.
- 19 19. The herein described method of treat- 55 ing hat bats and the like, which consists in advancing the bat in an unrolled condition between two rows of rollers having spiral threads on their peripheries with the threads of adjacent rollers running in opposite directions and the threads of opposed rollers running in the same direction, and causing some of the rollers to rotate at less peripheral speed than that at which the bat is advanced to create a succession of waves in each of the plies and advance the same throughout the bat.
- 20 20. The herein described method of treating hat bats and the like, which consists in advancing the bat by a plurality of rollers 60 having spiral ribs running in opposite directions, and maintaining the bat in saturated condition.
- 21 21. The herein described method of treating hat bats and the like, which consists in simultaneously and progressively shifting spaced portions of each ply in opposite directions and simultaneously shifting abutting portions of the two plies in opposite directions and maintaining the bat in saturated 65 condition.
- 22 22. The herein described method of treating hat bats and the like, which consists in progressively and successively applying pressure to the bat and advancing through each 70 ply of the bat zigzag waves spaced apart transversely of the direction in which the pressure is advanced, the waves in one ply being reversed to those of the other ply, and maintaining the bat in saturated condition.
- 23 23. The herein described method of treating hat bats and the like, which consists in advancing the bat in an unrolled condition beneath a series of rollers having spiral threads on their peripheries and with the threads of adjacent rollers running in opposite directions.
- 24 24. In a machine for shrinking hat bats and the like, means for progressively and successively applying pressure to the bat, 75

- means for simultaneously moving spaced portions of the plies of the bat back and forth in the plane of the plies and in opposite directions and transversely to the direction in which the pressure is advanced. 50
25. In a machine for shrinking hat bats and the like, a plurality of members between which the bats are passed in an unrolled and flatwise condition, and means on said members for simultaneously shifting spaced portions of each ply of the bat in opposite directions and abutting portions of the two plies in opposite directions. 55
- 10 26. In a machine for shrinking hat bats and the like, a plurality of rollers between which the bats are adapted to be passed in flatwise condition, means on said rollers for simultaneously shifting spaced portions and alternately shifting the same portions of each of the plies in opposite directions and for rotating the opposed rollers in opposite directions. 60
- 20 27. In a machine for shrinking hat bats and the like, a plurality of rollers between which the bats are passed in unrolled condition, adjacent rollers to each side of the bat having threads on their peripheries running in opposite directions, the threads on opposed rollers running in the same direction, and means for rotating the opposed rollers in opposite directions. 70
- 30 28. In a machine for shrinking hat bats and the like, means for advancing the bat, and means for forming zigzag waves in each ply of the bat in the direction in which the bat is advanced. 80
- 35 29. In a machine for shrinking hat bats and the like, a plurality of rollers between which the bats are passed in flatwise condition, and means on said rollers for forming and advancing zigzag waves in each of the plies extending in the direction in which the bats are advanced. 85
- 40 45 30. In a machine for shrinking hat bats and the like, means for simultaneously moving spaced portions and alternately moving the same portions of each of the plies in opposite directions and for forming in each of the plies zigzag waves. 50
31. In a machine for shrinking hat bats and the like, a plurality of rollers between which the bats are passed in flatwise condition, said rollers being provided on their peripheries with means for simultaneously shifting spaced portions and alternately shifting the same portions of each of the plies in opposite directions and for forming zigzag waves in each of the plies at right angles to the length of the rollers, and means for rotating said rollers. 55
32. In a machine for shrinking hat bats and the like, a plurality of rollers between which the bats are adapted to be passed in flatwise condition, means on said rollers for simultaneously shifting spaced portions and alternately shifting the same portions of each of the plies in opposite directions and shifting abutting portions of the two plies in opposite directions, and means for rotating the opposed rollers in opposite directions, some of said rollers being urged, under pressure, towards the opposed rollers. 65
33. In a machine for shrinking hat bats and the like, a plurality of rollers between which the bats are passed in unrolled condition, adjacent rollers to each side of the bat having threads on their peripheries running in opposite directions, the threads on opposed rollers running in the same direction, means for rotating the opposed rollers in opposite directions, and means for urging some of said rollers of each set under pressure towards the opposed rollers, said pressure rollers being adapted to rotate at less 75 peripheral speed than the driven rollers. 80
34. In a machine for shrinking hat bats and the like, means for supporting a bat, and a plurality of rollers adapted to engage a bat in unrolled condition on said supporting means, said rollers having means for forming and advancing zigzag waves in the bat and extending in the direction in which the bat is advanced. 90

HOMER A. GENEST.
